Primary Examiner — Katrina A Betton*(74) Attorney, Agent, or Firm* — Banner & Witcoff, Ltd.(57) **CLAIM**

The ornamental design for a vehicle, as shown and described.

DESCRIPTION

FIG. 1 is a perspective view of a vehicle showing our new design;

FIG. 2 is a top view thereof; and,

FIG. 3 is a portion of a side perspective view thereof.
The dot-dash lines immediately adjacent to the shaded areas define the bounds of the claimed design and form no part thereof. The broken lines showing the remainder of the vehicle represent unclaimed subject matter and form no part of the claimed design.**1 Claim, 3 Drawing Sheets**(56) **References Cited**
